UNITED STATES PATENT OFFICE.

HUGO NEWMAN, OF NEW YORK, N. Y.

EDUCATIONAL DEVICE.

1,028,378.

Specification of Letters Patent.

Patented June 4, 1912.

Application filed July 6, 1910, Serial No. 570,553. Renewed March 4, 1912. Serial No. 681,612.

To all whom it may concern:

Be it known that I, HUGO NEWMAN, a citizen of the United States, residing at New York, borough of Bronx, in the county 5 of New York and State of New York, have invented certain new and useful Improvements in Educational Devices, of which the following is a specification.

This invention relates to educational devices, the object of the invention being to provide an improved device of this character extremely simple in construction and operation, and therefore inexpensive to manufacture, and which is made up of two 15 sets of shiftable, readily removable and interchangeable strips, one set superimposed upon the other, and which sets of strips are so carried and supported that the device or chart may be reversible so that both sides 20 thereof may be used, one side as an arithmetical chart and the other side as a language chart, if preferred.

In the drawings accompanying and forming part of this specification, Figure 1 is 25 a face view of one side of this improved chart, with several of the horizontal strips partly broken away; Fig. 2 is a detail sectional view of a part thereof, taken in line 2-2 Fig. 1; Fig. 3 is a perspective view of 30 a portion of one of the vertical strips; Fig. 4 is a face view of another form of frame or support for supporting the strips; Fig. 5 is a perspective view of one corner of the 35 frame with the end stop-board removed; and Fig. 6 is a cross sectional view of Fig. 4.

Similar characters of reference indicate corresponding parts throughout the figures of the drawings.

This improved chart, in the preferred 40 form thereof shown, comprises a suitable rectangular frame 2 made up of upright end strips 3 and 4 and bottom and top strips 5 and 6, suitably connected together and provided with suitable means for maintaining 45 the shiftable educational strips in proper position.

In the form shown in Fig. 1 the upright end frames or strips 3 and 4 are connected by a series of horizontally extending slats 50 7 having located at intervals along the same headed pins 8, the spaces between the pins being substantially the width of a vertical strip. The horizontal slats are so spaced apart that the space between the pins crosswise of the frame will also be substantially 55 the width of the strip. Carried by one of

the end frame members are suitable stops 9, one for each horizontal strip, to limit the movement of the strips in one direction. Located crosswise of the frame is a series of 60 rows, shown as ten in number, of shiftable strips 10, which are readily removable and interchangeable one with another, and for which purpose the strips are shown provided at one side of the frame with extension portions 11 whereby they may be readily withdrawn from one or more rows and inserted in different rows, or a plurality thereof located one upon another in superimposed position in each row. Extending 65 vertically of the frame, and across, and therefore superimposed upon the horizontal rows of strips are a plurality of similarly formed strips 12 carrying, however, different characters from those carried by the 70 horizontally disposed strips. In the form shown in Fig. 1 the horizontally disposed strips are provided with numerals, while the vertically disposed strips are provided with 75 arithmetical signs, such as plus, minus, subtraction, multiplication and division, although various characters could be used on the vertical strips as well as on the others. For preventing the slippage of the vertical strips some suitable means may be used. In 80 the present instance each pair of pins at the bottom of the frame adjacent to a vertical strip is provided with some suitable elastic means, such as a rubber band, the tension of which maintains the vertical strips in position. One side of this frame may be used 85 for numerals and arithmetical signs, while the other side of the same chart may carry strips having letters of the alphabet thereon, or other characters. 90

In the form shown in Fig. 4, instead of providing the chart with the headed pins the horizontal strips are carried by suitable ways formed by grooving or recessing the end members of the frame, as at 14, suitable 100 upright intermediate members 15 having openings in alignment with the grooves in the end members being provided to properly support and guide the horizontal strips when the same are shifted back and forth 105 crosswise of the frame. Similarly formed grooves or recesses are provided in the top and bottom members of the frame for the vertical strips, and to maintain these strips in position suitable spring formed members 110 16 are provided carried by the bottom member of the frame. In the form shown in

Fig. 4 the horizontal and vertical strips, which are the same as those shown in Fig. 1, are provided with letters of the alphabet, and it will be observed that several strips 5 in each horizontal row may be superimposed upon each other, and that several vertical strips in each vertical row may be superimposed upon each other, while one set of strips, as for instance the vertical set, is superimposed upon the horizontal set, and that each strip is readily shiftable as well as removable, so that they may be interchanged one with another, and thus by a very simple arrangement permitting a great many combinations of words and figures, while one side of either chart may be used for combinations of figures while the other side is used for combinations of letters or words, thus providing not only a reversible chart, but 10 one in which any of the strips may not only be readily shifted to change the combination but may be readily withdrawn or removed and inserted into a different place, as occasion may require.

25 In practice the ten rows of horizontal strips will be provided with ten vertical columns of characters, either letters of the alphabet or figures, so that by shifting the vertical or horizontal strips, or both, a great many combinations can be provided without even the removal of any of the strips. For instance, by an inspection of Fig. 1 it will be observed that in using the educational chart the vertical strip at the left carries the minus sign, while the intermediate vertical strip carries the plus sign, the shifting of which, however, brings into view a vertical strip therebeneath carrying the division sign, while the topmost strip at the right 30 carries the minus sign, which by shifting downward brings into view another strip carrying the multiplication sign. Of course, it will be obvious that each strip, as shown in Fig. 3, may carry various signs, so that 35 by means of this chart an almost inconceivable number of combinations of figures or letters can be made with a comparatively small number of strips and by a very simple arrangement and supporting thereof, thus entirely doing away with the use of endless bands or interwoven strips or other complicated features of this character.

40 In both forms of the frame herein shown it will be observed that the series of rows of horizontal and vertical strips are carried by suitable guideways, the guideways in the form shown in Fig. 1 being obtained by means of headed pins, while in the form shown in Fig. 4 they are obtained by properly recessing or grooving the end frame members and by providing intermediate guide supports. It will be observed that in the structure shown in Fig. 1, as well as in that shown in Fig. 4, the guideways constitute a means of not only properly guiding

the strips, but prevent the falling forward thereof in use, and that in the structure shown in Fig. 1 the same headed pins constituting these guideways for the horizontal strip also form the guideways for the vertical strips, and that in whatever position the horizontal or vertical rows of strips may be shifted so they will always be properly guided and prevented from falling forward. 70

In the form shown in Fig. 4, instead of using the headed pins 9 shown in Fig. 1 to limit the shifting movement of the horizontal strips, the end of the upright frame member shown in Fig. 5 is provided with a stop-board 9' against which the inner ends of the strips contact and so limit their shifting movement. 75

As will be understood from the foregoing description, the strips of the several rows of each set are interchangeable with each other, and the strips of one set may be interchanged with those of another, the strips being shown all of the same width. In the present construction the vertical strips are of such length that they will project from either the top or the bottom, so that they can be manipulated from either the top or bottom of the frame, the resilient holding means holding them in any of their adjusted positions. 80

90 I claim as my invention:

1. In an educational device of the character set forth, the combination of a supporting frame, a set of shiftable, removable and interchangeable strips of substantially the same dimensions carrying characters located in horizontal rows, one or more of the rows having strips superimposed one upon another, the strips of the several rows being interchangeable, and one or more rows 100 of vertically shiftable strips carrying characters, one or more of the vertical rows having character carrying strips superimposed one upon another. 105

2. In an educational device of the character set forth, the combination of a supporting frame, a set of shiftable, removable and interchangeable strips of substantially the same dimensions carrying characters, located in horizontal rows, the strips of the several rows being interchangeable, and a set of shiftable, removable and interchangeable strips of substantially the same dimensions carrying characters and located in vertical rows, the strips of the several rows 115 being interchangeable. 120

3. In an educational device of the character set forth, the combination of a supporting frame, a set of shiftable, removable and interchangeable strips of substantially the same dimensions, carrying characters, located in horizontal rows, one or more of the rows having strips superimposed one upon another, the strips of the several rows being interchangeable, and a set of vertically 125 130

shiftable, removable and interchangeable strips of substantially the same dimensions, carrying characters, located in vertical rows, one or more of the vertical rows having 5 character carrying strips superimposed one upon another and the strips of the several vertical rows being interchangeable.

4. In an educational device of the character set forth, the combination of a supporting frame, a set of shiftable, removable and interchangeable strips of substantially the same dimensions carrying characters located in horizontal rows on each side of said frame, the strips on one side having characters differing from those on the other side, and the strips of the several rows and of the two sides being interchangeable, and one or more rows of vertically disposed character carrying strips shiftable transversely of the horizontally disposed strips located on each side of the frame.

5. In an educational device, the combination of a supporting frame, a set of shiftable, removable and interchangeable strips 25 carrying characters and located in horizontal rows, and means for guiding said strips and comprising ways formed by headed pins.

6. In an educational device, the combination of a supporting frame, a set of shiftable, removable and interchangeable strips 30 of substantially the same dimensions carrying characters and located in horizontal rows, the strips of the several rows being interchangeable, means for guiding said strips, and one or more superimposed vertically shiftable character carrying strips.

7. In an educational device, the combination of a supporting frame, a set of shiftable, removable and interchangeable strips 40 carrying characters and located in horizontal rows, means for guiding said strips, a set of vertically shiftable character carrying strips, adapted to project above and below the frame for manipulation from either end 45 of the strip, and means for maintaining such vertical strips in any of their adjusted positions.

8. In an educational device, the combination of a supporting frame, a set of shiftable, removable and interchangeable strips 50 carrying characters and located in horizontal rows, means for guiding said strips, one or more superimposed, vertically shiftable character carrying strips, and resilient means for maintaining the strips in position.

9. In an educational device, the combination of a supporting frame, and two sets of superimposed, shiftable, removable and interchangeable strips of substantially the 60 same dimensions carrying characters, one set comprising a series of horizontal rows of strips and the other a plurality of vertical rows of strips of substantially the same dimensions and one or more of the rows of 65 each set having strips superimposed one upon another, the rows of strips of each set being interchangeable and the strips of one set being interchangeable with those of the other set.

10. In an educational device, the combination of a supporting frame, two sets of superimposed, shiftable, removable and interchangeable strips carrying characters, one set comprising a series of horizontal 75 rows of strips and the other a plurality of vertical rows of strips, means for guiding the horizontal rows and the vertical rows of strips, and resilient means for maintaining the vertical rows of strips in their shifted position.

11. In an educational device, the combination of a supporting frame, two sets of superimposed and shiftable character carrying strips one set located in horizontal 85 rows and the other in vertical rows, and resilient means for maintaining the vertical rows of strips in any of their shifted positions.
